DESIGN FOR A GAME DISK

Walter A. Troth, Brooklyn, N. Y.

Application April 20, 1938, Serial No. 76,627

Term of patent 14 years

To all whom it may concern:

Be it known that I, Walter A. Troth, a citizen of the United States, residing at Brooklyn, in the county of Kings and State of New York, have invented a new, original, and ornamental Design for a Game Disk, of which the following is a specification, reference being had to the accompanying drawing, forming part thereof.

The characteristic features of my design reside in a plurality of concentric ball races, each having a plurality of ornamental ball stops.

In the drawing:

Fig. 1 is a plan view of a game disk, showing my new design.

Fig. 2 is an edge view thereof.

I claim:

The ornamental design for a game disk, as shown and described.

WALTER A. TROTH.
